ABSTRACT OF THE DISCLOSURE

Disclosed herein are certain germicidal detergent compositions, and particularly, iodophors wherein the iodine carrier is an alkylene oxide condensate having amphoteric properties. Such germicides are especially suitable for the poultry and dairy industry.

This invention is concerned with germicidal detergent compositions, including compositions known as iodophors, an iodophor being a composition containing iodine and a carrier in which the carrier is a compound which increases the solubility of iodine in aqueous systems.

In an iodophor, the iodine is apparently chemically bound to, and/or complexed with, the carrier.

Among the known iodophors are those comprising iodine and a surfactant. To form germicidal compositions, these iodophors are frequently formulated with phosphoric acid to yield aqueous concentrates which are finally diluted with water by the end-user.

A most important characteristic of iodophors in their diluted ready-to-use form is that they should possess a low iodine vapour pressure combined with a high and constant "available" iodine content, by which is meant that at least 50% of the total iodine present should be titratable with thiosulphate solution and that this titratable quantity should remain constant over a period of time.

It has now been found that iodophors which possess the above characteristics to a marked degree in comparison with many iodophors based on conventional surfactants, such as non-ionic surfactants, can be made by using a surfactant having amphoteric properties.

Based on the above discovery, the present invention provides a germicidal detergent composition containing iodine and a water-soluble amphoteric surfactant. The composition is preferably in the form of a homogeneous liquid or semi-solid solution which advantageously is an aqueous solution also containing phosphoric acid. The compositions may contain one or more additional non-amphoteric, e.g., anionic or non-ionic, surfactants if these are required to confer additional detergency or to act as clarifying agents if the composition in their diluted form should show a tendency towards cloudiness. A low molecular weight alcohol such as isopropyl alcohol may also be included as a clarifying agent.

Whilst many amphoteric surfactants can be used, those preferred are alkylene oxide condensates containing groups which impart amphoteric properties, e.g., amine and sulfate groups. Examples of such surfactants, which have been found to be of special utility, are those comprising mixtures of compounds of the formula:

where R_1 , R_2 and R_3 are alkyl groups containing a total of 7 to 24 carbon atoms, R_4 is hydrogen or C_1-C_4 alkyl, particularly methyl, m is an integer and X is hydrogen or

2

an alkali metal, preferably sodium, the mixture containing an average of 6-100, and preferably 12-50

groups per molecule. Preferably, compounds of the above formula are ethylene oxide derivatives in which case R_4 will be hydrogen exclusively; but the compounds may be derived from other alkylene oxides, e.g. mixtures of ethylene and propylene oxides. It is also preferred that compounds of the above formula be derived from isomeric mixtures of amines of the formula

and which contain 12 to 24 carbon atoms, e.g. mixtures of amines containing 12 to 15 carbon atoms or 18 to 24 carbon atoms. Surfactants of the class just described are of particular utility in forming ready-for-use germicidal compositions of low iodine vapour pressure combined with a high and constant "available" iodine content.

Other usable amphoteric surfactants are those of the classes set forth below:

(1) Amino-substituted alkanoic acids and salts thereof, such as those containing from 2 to about 8 carbon atoms in the alkanoic acid portion and having as a substituent an amino group whose remaining two valences are satisfied by hydrogen and a C_8-C_{18} hydrocarbon or acyl group. A typical sub-class of such compounds is represented by the formula:

where R^1 represents a surface activity producing group with 8 to 18 or more carbon atoms and M is a salt-forming cation or hydrogen.

(2) Betaine type of compounds such as betaine derivatives of the formula:

where R^1 is as defined above and R^2 , R^3 and R^4 are shorter chain alkyl (or alkylene in the case of R^3) groups, e.g. methyl or methylene.

(3) Compounds having the formula:

where R^1 is as defined above and M is a salt-forming cation or hydrogen.

In general, the weight ratio of amphoteric surfactant to iodine will range from 1:1 to 50:1, and preferably ranges from 2:1 to 10:1. The amount of iodine in a concentrate intended to be diluted by the end-user will generally be from 0.5 to 6% by weight, preferably 1 to 3% and the amount of amphoteric surfactant in this type of composition will generally range from 2 to 25% by weight.

When, as is preferred, phosphoric acid is present, concentrates for dilution with water by the end-user will generally contain the equivalent of about 2 to 50% by weight, typically 4 to 30% by weight, 85% phosphoric acid.

If a non-amphoteric surfactant is included in the composition such surfactant may be one of the conventional non-ionic materials such as condensates of an alkylene oxide, e.g., ethylene and/or propylene oxide, and a hydrophobic compound containing an active hydrogen atom. Preferred non-ionic surfactants are condensates of octyl or nonyl phenol and 6 to 100 moles of ethylene oxide. Alternatively there may be used anionic surfactants such as sulfonated or sulfated materials.

The invention is illustrated by the following examples in which Surfactants A-F are those identified below:

Surfactant A is a mixture of amphoteric compounds of the formula:

where the

residues are derived from a commercial mixture of isomeric amines having 12-15 carbon atoms and exhibiting a tertiary alkyl structure at the point of attachment to the amino nitrogen atom and m is an integer; there being an average of 15 $-\text{CH}_2\text{CH}_2\text{O}-$ groups per mole of amphoteric compound.

Surfactant B is a non-ionic condensate of ocyphenol and 9-10 moles of ethylene oxide.

Surfactant C is a product available commercially as Ambiteric D from Gloves (Chemicals) Ltd., Leeds, England; it is believed to consist predominantly (85-90%) of molecules of the formula:

where R^1 represents long chain alkyl, at least 90% of such alkyl radicals being dodecyl, R^2 and R^4 are methyl and R^3 is methylene.

Surfactant D is a product available as Ambiteric H and is similar to Ambiteric D described above except that at least 90% of the R^1 alkyl radicals are hexadecyl.

Surfactant E is a product available commercially as Deriphath 170C from General Mills, Inc., Illinois, United States of America. This product contains ca. 50% N-lauryl myristyl β -aminopropionic acid.

Surfactant F is a product available commercially as Empigen BB from Marchon Products Ltd., Whitehaven, England; it contains 30% active ingredient which is similar to the active component in Surfactant C described above except that the R^1 radicals are predominantly lauryl/myristyl.

In the examples which now follow parts and percentages are on a weight basis and in all instances the iodophors described were made by mixing the iodine and the amphoteric surfactant at a temperature of 35° C. and for a sufficient time to result in the iodophor.

Example I

There are intimately mixed 3.5 parts of iodine and 20 parts of Surfactant A to form a homogeneous iodophor which can be formulated into a germicidal concentrate for the dairy and poultry industries.

Example II

23.5 parts of the iodophor of Example I are mixed with 50 parts of phosphoric acid (85%) and water is added to make 125 parts. The product on dilution with water forms an excellent germicidal detergent which passes the test described by Hoy et al. in the Journal of Applied Bacteriology 23 (2), pp. 359-371 and which is therefore particularly suited for use in the dairy industry.

Example III

23.5 parts of the iodophor of Example I are mixed with 6 parts of phosphoric acid (85%) and water is added to make 135 parts. The product on dilution with water provides a germicidal detergent suitable for the poultry industry.

Example IV

There are intimately mixed 3.5 parts of iodine and 10 parts of Surfactant A. To the iodophor thus made are

added 5 parts phosphoric acid (85%), 7 parts of Surfactant B and water to make a total of 100 parts. There results a germicidal detergent composition suitable for use in the poultry industry after suitable dilution with water.

5

Example V

There are intimately mixed 3.5 parts of iodine and 10 parts of Surfactant A and to the iodophor thus obtained there are added 50 parts phosphoric acid (85%), 10 parts of Surfactant B and water to make 100 parts. There results a germicidal detergent composition useful in the dairy industry after dilution with water.

10

Example VI

15 (a) There are intimately mixed 3.5 parts of iodine and 12 parts of Surfactant C to form an iodophor. There are then added 5 parts of phosphoric acid (85%), 12 parts of Surfactant B and water to make 120 parts. The product is suitable as a germicide for the poultry industry after dilution with water.

20

(b) Part (a) is repeated except that Surfactant C is replaced by the same quantity of Surfactant D, 10 parts of the water is replaced by 10 parts of isopropyl alcohol and an additional 8 parts of Surfactant B are added.

25

(c) Part (a) is repeated except that an additional 45 parts of phosphoric acid (85%) are added. The product is suitable for the dairy industry after dilution.

30

(a) There are intimately mixed 5 parts of iodine and 30 parts of Surfactant E to form an iodophor. There are then added 7.5 parts of phosphoric acid (85%), 20 parts of Surfactant B and water to make 180 parts. The product is a germicide suitable for use in the poultry industry.

35

(b) Part (a) is repeated except that 75 parts of phosphoric acid (85%) are added and water is added to make 200 parts. The product is suitable for use in the dairy industry after dilution with water.

40

Example VII

(a) There are intimately mixed 5 parts of iodine and 45 parts of Surfactant F to form an iodophor. To the iodophor are added 7.5 parts of phosphoric acid (85%), 20 parts of Surfactant B, 10 parts isopropyl alcohol and water to make 180 parts. The product is suitable for use in the poultry industry.

45

(b) Part (a) is repeated except that 75 parts of phosphoric acid (85%) are used and water is added to make 210 parts. The product is useful in the dairy industry after dilution with water.

50

I claim:

1. An iodophor composition consisting essentially of iodine and, as water-soluble amphoteric surfactant, a mixture of compounds of the formula:

55

where R_1 , R_2 and R_3 are alkyl groups containing a total of 7 to 24 carbon atoms, R_4 is selected from the group consisting of hydrogen and alkyl groups having 1 to 4 carbon atoms, m is an integer having an average value of 6 to 100 and X is selected from the group consisting of hydrogen and the alkali metals, the weight ratio of surfactant to iodine ranging from 1:1 to 50:1.

60

2. A composition according to claim 1, wherein R_4 is hydrogen, X is sodium and the mixture contains an average of 12 to 50 $-\text{CH}_2\text{CH}_2\text{O}-$ groups per molecule.

65

3. A composition according to claim 1, wherein the weight ratio of surfactant to iodine is from 2:1 to 10:1.

70

4. A concentrate for dilution with water to form a germicidal detergent composition which consists essentially of iodine, phosphoric acid and, as amphoteric surfactant, a mixture of compounds of the formula:

where R_1 , R_2 and R_3 are alkyl groups containing a total of 7 to 24 carbon atoms, R_4 is selected from the group consisting of hydrogen and alkyl groups having from 1 to 4 carbon atoms, m is an integer having an average value of 6 to 100 and X is selected from the group consisting of hydrogen and the alkali metals, the weight ratio of surfactant to iodine ranging from 1:1 to 50:1. 5

5. A concentrate according to claim 4 which contains 0.5 to 6% by weight of iodine and wherein the weight ratio of surfactant to iodine is from 2:1 to 10:1.

6. A concentrate according to claim 4 which contains 15 the equivalent of 2 to 50% by weight of 85% phosphoric acid.

7. A concentrate according to claim 4 which also contains a nonionic surfactant comprising a condensate of an alkylene oxide and a hydrophobic compound containing an active hydrogen atom.
